ABSTRACT: The invention concerns new (4aRS,5SR,9bSR)-, (4aRS,5SR,9bRS)- and (4aRS,5RS,9bRS)-1,3,4,4a,5,9b-hexahydro-5-phenyl-2H-indeno[1,2-c]pyridines of the formula:

wherein R₁ is hydrogen, lower alkyl, fluorine, bromine or chlorine, and each of R₂, R₃ and R₄ are hydrogen, lower alkyl, fluorine, bromine, chlorine, lower alkoxy, lower alkylthio or trifluoromethyl. A process for the production thereof and intermediates therefor are also described. The compounds are serotonin-antagonists and furthermore inhibit hematoblast aggregation.

1,3,4,4A,5,9B-HEXAHYDRO-5-PHENYL-2H-INDENO[1,2-C]PYRIDINES

IMPROVEMENTS IN OR RELATING TO ORGANIC COMPOUNDS

The present invention relates to new (4aRS,5SR,9bSR)-, (4aRS,5SR,9bRS)- and (4aRS,5RS,9bRS)-1,3,4,4a,5,9b-hexahydro-5-phenyl-2H-indeno[1,2-c]pyridines of formula I,

in which

R_1 signifies hydrogen, a lower alkyl radical, fluorine, bromine or chlorine, and each of

R_2 , R_3 and R_4 signifies hydrogen, a lower alkyl radical, fluorine, bromine, chlorine, a lower alkoxy, a lower alkylthio or the trifluoromethyl radical, and to a process for the production thereof.

Compounds of formula I have the fundamental structure represented by formula IX.

IX

The compounds I have three centers of asymmetry in the tricyclic ring system, i.e. the carbon atoms in positions 4a, 5 and 9b. Therefore, theoretically there may exist four isomers, which differ from each other by the position of the hydrogen atoms at the centers of asymmetry.

The nomenclature of R. S. Cahn, C. K. Ingold and V. Prelog, *Angewandte Chemie* 78, 413 (1966), is used.

Name	Position of the hydrogen atoms
(4aRS,5SR,9bSR)	4a/9b trans 4a/5 trans
(4aRS,5SR,9bRS)	4a/9b cis 4a/5 trans
(4aRS,5RS,9bRS)	4a/9b cis 4a/5 cis

According to the invention the new indenopyridine derivatives of formula I are obtained by reacting a compound of formula II,

II

in which R_1 and R_2 have the above significance, and having the same configuration as the desired final product of formula I, with a compound of formula III,

III

in which R_3 and R_4 have the above significance, and X signifies the acid radical of a reactive ester, in a solvent which is inert under the reaction conditions and in the presence of a basic condensation agent.

When the purpose of the invention is effected using one isomeric form of a compound of formula II as starting material, then the same isomeric form of a compound of formula I is obtained.

The invention is explained in detail below:

- 10 A compound of formula II in a solvent which is inert under the reaction conditions, e.g. in a di(lower)alkyl-carboxylic acid amide such as dimethyl formamide, or in a lower alcohol such as ethanol, or in a ketone such as acetone, is reacted with a compound of formula III, preferably at an elevated temperature between 60° and 150° C., in the presence of a basic condensation agent, the reaction having a duration of from one-half to 24 hours, but normally 1 to 4 hours. Examples of suitable basic condensation agents are: alkali metal carbonates such as sodium or potassium carbonate, or lower tertiary alkyl amines such as triethyl amine, or an excess of an equivalent of the compound of formula II.

The lower alkyl radicals represented by the symbol R_1 preferably have one to four, especially one to two carbon atoms, the lower alkyl, alkoxy and alkylthio radicals represented by the symbols R_2 , R_3 and R_4 preferably have one to four, especially one to two carbon atoms.

One process for the production of the compounds of formula II is characterized in that a compound of formula IIa,

IIa

in which R_1 and R_2 have the above significance, and R_5 signifies the methyl or benzyl radical, is reacted with an ester of chloroformic acid of formula IV,

- 30 50 in which R_6 signifies a lower alkyl radical, a phenyl or benzyl radical, to give the corresponding urethane, and these urethanes are subsequently hydrolyzed.

The reaction of a compound of formula IIa with a chloroformic acid ester of formula IV is preferably effected in a solvent which is inert under the reaction conditions, e.g. anhydrous benzene, and at the boiling temperature of the reaction mixture. For this reaction chloroformic acid esters of formula IVa,

- 60 65 in which R_6' signifies a lower alkyl radical, are especially preferred as starting materials. The resulting urethanes may either be purified in manner known per se, or used as such for the subsequent urethane splitting.

The removal of the COOR₆ radical from the urethanes may be effected with an acid, e.g. a mineral acid such as hydrochloric acid, or a base, e.g. an alkali metal hydroxide such as potassium or sodium hydroxide, in a lower alcohol such as n-butanol, preferably at the boiling temperature of the reaction mixture. Hydrolysis with an alkali metal hydroxide may result in a total or partial rearrangement of the (4aRS,5RS,9bRS) compounds into (4ARS,5SR,9bRS) compounds.

Compounds of formula IIa may be obtained by
a. cyclizing a compound of formula V,

5 in which R₁ and R₅ have the above significance,
is reacted with an organometallic compound of formula VIII,

VII

10

VIII

or of formula VIIIa,

VIIIa

15

Va

in which R₁ and R₅ have the above significance,
to produce a compound of formula IIb,

IIb

in which R₁ and R₅ have the above significance,
or
c. reducing a compound of formula IV,

VI

in which R₁, R₂ and R₅ have the above significance,
to produce a (4aRS,5RS,9bRS) compound of formula IIa, or
d. heating a (4aRS,5RS,9bRS) compound of formula IIa in an
alkaline medium to produce a (4aRS,5SR,9bRS) compound
of formula IIa.

Processes (a) and (b) mainly yield (4aRS,5SR,9bSR) and
(4aRS,5SR,9bRS) compounds, the relationship of the isomers
being dependent on the nature of the substituents R₁ and R₂.

The cyclization in accordance with processes a and b may
be effected with polyphosphoric acid, optionally in the
presence of a solvent which is inert under the reaction conditions,
e.g. a cyclic hydrocarbon such as benzene, toluene,
xylene or tetralin, for a period of between 1 and 24 hours at a
temperature between 80° and 150° C.

A process used for the production of compounds of formula
V is characterized in that a compound of formula VII,

20 in which R₂ has the above significance, and X' signifies
chlorine or bromine,
in a solvent which is inert under the reaction conditions, and
the resulting complex is hydrolyzed.

25 For the reaction of compounds of formula VII with com-
pounds of formula VIII or VIIIa a cyclic or open-chain ether
such as diethyl ether or tetrahydrofuran may, for example, be
used as solvent which is inert under the reaction conditions,
and the reaction is preferably effected at a temperature

30 between 20° and 70° C. Benzyl magnesium bromide or benzyl
lithium may, for example, be used as organometallic com-
pound of formula VIII or VIIIa.

Compounds of formula VII may be produced by reacting a
35 2-phenyl-acrylic acid ester appropriately substituted on the
phenyl radical with a 3-aminopropionic acid ester ap-
propriately substituted on the nitrogen atom, cyclizing the ad-
dition product by treatment with a basic condensation agent,
and hydrolyzing and decarboxylating the resulting compound.

Compounds of formula Va may be obtained by reacting a
40 compound of formula X,

X

45 in which R₅ has the above significance,
with at least two mols of a compound of formula VIIIb,

VIIIb

50 55 in which R₁ and X' have the above significance,
in a solvent which is inert under the reaction conditions,
hydrolyzing the reaction product and reducing the resulting
compound of formula XI,

XI

60

70

in which R₁ and R₅ have the above significance.
The compounds of formula I and their pharmaco-
logically

75

tolerable acid addition salts are useful because they possess pharmacological activity in animals. More particularly, the compounds are useful as serotonin-antagonists, as indicated by the serotonin toxicity test in guinea pigs. The dosage administered will naturally vary depending on the compound employed, the mode of administration and the treatment desired. However, satisfactory results are obtained in test animals at doses from about 0.5 to about 20 mg./kg. of body weight. As indicated by the said serotonin-antagonist properties, the compounds can be employed in the treatment of migraine, the total daily dose for larger mammals being from about 1 to about 30 mg. Divided dosage forms suitable for oral application contain about 0.3 to about 15 mg. of the compound admixed with a solid or liquid carrier or diluent.

The compounds are furthermore useful in the treatment of thrombosis as indicated by their properties in inhibiting hematoblast aggregation, this property being illustrated in the ADP-induced hematoblast aggregation test carried out in vitro. Doses administered will naturally vary depending on the compound employed, the mode of administration and the treatment desired. However, indicated doses in warm-blooded animals are between about 0.5 to about 10 mg./kg. body weight. For larger mammals the total daily dosage is in the range of from about 10 to about 400 mg., and dosage forms for oral application contain from about 3 to about 200 mg. of the compound admixed with solid or liquid carrier or diluent.

The compounds of formula I or their physiologically tolerable acid addition salts may be used as medicaments on their own or in the form of appropriate medicinal preparations with pharmacologically inert adjuvants.

Insofar as the production of the starting materials is not described, these are known or may be produced in accordance with known processes or in a manner analogous to the processes described herein or to processes known per se.

In the following nonlimitative examples all temperatures are indicated in degrees Centigrade and are uncorrected.

EXAMPLE 1

(4aRS,5SR,9bSR)-1,3,4,4a,5,9b-hexahydro-7-methyl-2-phenacyl-5-p-tolyl-2H-indeno[1,2-c]pyridine

A solution of 7.9 g. of phenacyl chloride in 50 cc. of dimethyl formamide is added dropwise at room temperature to a suspension of 14.4 g. of (4aRS,5SR,9bSR)-1,3,4,4a,5,9b-hexahydro-7-methyl-5-p-tolyl-2H-indeno[1,2-c]pyridine and 10.9 g. of sodium carbonate in 100 cc. of dimethyl formamide. The reaction mixture is subsequently heated in an oil bath of 130° for 2 hours, is then cooled to room temperature and poured on 500 g. of ice. The aqueous phase is shaken out thrice with 500 cc. amounts of diethyl ether, the ether phase is washed with water, dried over magnesium sulfate, purified with animal charcoal and concentrated to a volume of about 200 cc. at reduced pressure. After cooling in a refrigerator the title compound crystallizes. m.p. 85°-86°.

The following compounds of formula I may be obtained in a manner analogous to that described in example 1 (examples 2 to 17):

Example	R ₁	R ₂	R ₃	R ₄	Configuration	Phys. chem. constants
2	Cl	4-Cl	H	H	4aRS, 5SR, 9bSR	M.P. 95-100°.
3	Cl	4-Cl	H	H	4aRS, 5SR, 9bSR	M.P. of the hydrogen fumarate 190-191°.
4	H	H	4-Br	H	4aRS, 5SR, 9bSR	M.P. 138-139°.
5	H	H	4-Cl	H	4aRS, 5SR, 9bSR	M.P. 147-148°.
6	H	H	2-Cl	5-Cl	4aRS, 5SR, 9bSR	M.P. 128-129°.
7	H	H	2-CH ₃	H	4aRS, 5SR, 9bSR	M.P. 106-107°.
8	H	H	3-CH ₃	H	4aRS, 5SR, 9bSR	M.P. 121-123°.
9	H	H	4-CH ₃	H	4aRS, 5SR, 9bSR	M.P. 127-129°.
10	H	H	3-OCH ₃	H	4aRS, 5SR, 9bSR	M.P. 112-114°.
11	H	H	4-OCH ₃	H	4aRS, 5SR, 9bSR	M.P. 108-110°.
12	H	H	H	H	4aRS, 5SR, 9bRS	M.P. of the hydrochloride 237-240° (decomp.).
13	H	H	H	H	4aRS, 5SR, 9bRS	M.P. of the hydrogen fumarate 193-196° (decomp.).
14	CH ₃	4-CH ₃	H	H	4aRS, 5SR, 9bRS	M.P. of the hydrogen fumarate 185° (decomp.).
15	Cl	4-Cl	4-OCH ₃	H	4aRS, 5SR, 9bRS	M.P. of the hydrogen fumarate 197-202° (decomp.).
16	Cl	4-Cl	3-CH ₃	H	4aRS, 5SR, 9bRS	M.P. of the hydrogen fumarate 192-194° (decomp.).
17	Cl	4-Cl	3-OCH ₃	4-OCH ₃	4aRS, 5SR, 9bRS	M.P. of the hydrogen fumarate 210-212° (decomp.).

EXAMPLE 18

(4aRS,5SR,9bSR)-1,3,4,4a,5,9b-hexahydro-2-phenacyl-5-phenyl-2H-indeno[1,2-c]pyridine

8.5 g. of anhydrous sodium carbonate are added to a solution of 10.0 g. of (4aRS,5SR,9bSR)-1,3,4,4a,5,9b-hexahydro-5-phenyl-2H-indeno[1,2-c]pyridine in 75 cc. of N,N-dimethyl formamide, and the mixture is heated to 100°. 12.4 g. of phenacyl chloride are added portionwise at the same temperature during the course of 2 hours, the reaction mixture is stirred at the same temperature for a further 30 minutes, is cooled to 20° and is poured into 200 cc. of a 20 percent common salt solution. The precipitated product is extracted with methylene chloride, the organic solution is washed with water, dried over sodium sulfate and the solvent is removed by distillation at reduced pressure. The oily residue is then dissolved in 100 cc. of ethanol, the pH value of the resulting solution is adjusted to 3 with hydrochloric acid in ethanol, and 10 cc. of ether are added. The mixture is allowed to stand at 0°, whereupon the precipitated hydrochloride of the title compound, having a m.p. of 250°-255°, is filtered off.

This hydrochloride is suspended in 100 cc. of water and 300 cc. of methylene chloride, the suspension is made alkaline with a caustic soda solution, the organic phase is separated and the aqueous phase is again shaken out twice with methylene chloride. The combined extracts are washed with water, dried over sodium sulfate and the solvent is removed by evaporation at reduced pressure. The residue is crystallized from ethanol, whereby (4aRS,5SR,9bSR)-1,3,4,4a,5,9b-hexahydro-2-phenacyl-5-phenyl-2H-indeno[1,2-c]pyridine, having a m.p. of 103.3°-105°, is obtained.

The compounds used as starting materials may be obtained as follows:

EXAMPLE 19

(4aRS,5SR,9bSR)-1,3,4,4a,5,9b-hexahydro-7-methyl-5-p-tolyl-2H-indeno[1,2-c]pyridine (for example 1)

A solution of 28 g. of chloroformic acid ethyl ester in 40 cc. of benzene is added dropwise at room temperature during the course of 10 minutes to a solution of 19 g. of (4aRS,5SR,9bSR)-1,3,4,4a,5,9b-hexahydro-2,7-dimethyl-5-p-tolyl-2H-indeno[1,2-c]pyridine in 150 cc. of benzene. The reaction mixture is then heated at reflux for 3 hours, is subsequently cooled to 20° washed with 2 N hydrochloric acid and with water and dried over sodium sulfate. After removing the solvent by distillation at reduced pressure, the residue is dissolved in 150 cc. of n-butanol, 73 g. of potassium hydroxide are added and the mixture is stirred in an oil bath of 130° for 1½ hours. After cooling to 70° the mixture is diluted with 300 cc. of benzene

and washed with water until neutral. After drying over magnesium sulfate the solvent is removed by distillation, whereby the title compound distils over at 194°/0.01 mm. of Hg. The compound obtained in crystalline form from ethanol/water (6:4) has a m.p. of 45°-46°.

The following compounds of formula II may be obtained in a manner analogous to that described in example 19 (examples 20 to 23):

Example	R ₁	R ₂	Configuration	Phys. chem. constants	For Ex.
20	Cl	4-Cl	4aRS, 5SR, 9bRS	B.P. 210°/0.06 mm. of Hg	2
21	Cl	4-Cl	4aRS, 5SR, 9bRS	B.P. 175-180°/0.01 mm. of Hg	3, 15, 16, 17
22	CH ₃	4-CH ₃	4aRS, 5SR, 9bRS	M.P. of the hydrogen fumarate 210-213°	14
23	H	H	4aRS, 5SR, 9bRS	M.P. of the hydrochloride 292-294°	4-11 and 18

EXAMPLE 24

(4aRS,5RS,9bRS)-1,3,4,4a,5,9b-hexahydro-2-methyl-5-phenyl-2H-indeno[1,2-c]pyridine (for example 12)

A solution of 12 g. of (4aRS,5RS,9bRS)-1,3,4,4a,5,9b-hexahydro-2-methyl-5-phenyl-2H-indeno[1,2-c]pyridine in 120 cc. of absolute benzene is added dropwise at 70°-75° during the course of half an hour to a solution of 15 g. of chloroformic acid ethyl ester in 60 cc. of benzene. The mixture is then boiled at reflux for 2½ hours, is cooled, some precipitated (4aRS,5RS,9bRS)-1,3,4,4a,b 5,9b-hexahydro-2-methyl-5-phenyl-2H-indeno[1,2-c]pyridine hydrochloride is filtered off and the filtrate is concentrated by evaporation. The resulting oily, crude (4aRS,5RS,9bRS)-2-ethoxycarbonyl-1,3,4,4a,5,9b-hexahydro-2-methyl-5-phenyl-2H-indeno[1,2-c]pyridine is boiled at reflux for 16 hours with a mixture of 75 cc. of glacial acetic acid and 75 cc. of concentrated hydrochloric acid. The mixture is evaporated to dryness in a vacuum, the residue is dissolved in a small amount of isopropanol and ether is added, whereupon the hydrochloride of (4aRS,5RS,9bRS)-1,3,4,4a,5,9b-hexahydro-2-methyl-5-phenyl-2H-indeno[1,2-c]pyridine crystallizes. It is recrystallized from isopropanol/ether and then has a m.p. of 230°-232° (decomp.).

The following compound of formula II may be obtained in a manner analogous to that described in example 24 (example 25):

Example	R ₁	R ₂	Configuration	Phys. chem. constants	For Ex.
25	H	H	4aRS, 5SR, 9bRS	M.P. of the hydrochloride 287-289° (dec.)	13

EXAMPLE 26

(4aRS,5RS,9bSR)-1,3,4,4a,5,9b-hexahydro-2,7-dimethyl-5-p-tolyl-2H-indeno[1,2-c]pyridine (for example 19)

35 g. of 4-(α -hydroxy-p-methylbenzyl)-1-methyl-3-p-tolyl-piperidine are added during the course of 5 minutes to 280 g. of polyphosphoric acid preheated to 100°. The reaction mixture is stirred at 130° for 30 minutes and subsequently poured on 200 g. of ice. The mixture is then made alkaline with a 5 N caustic soda solution and is shaken out thrice with 400 cc. of diethyl ether. After washing with water, drying over magnesium sulfate is effected, the solvent is removed by distillation and the oily residue is distilled in a high vacuum. (4aRS,5SR,9bSR)-1,3,4,4a,5,9b-hexahydro-2,7-dimethyl-5-p-tolyl-2H-indeno[1,2-c]pyridine distils over at 165°-170°/0.1 mm. of Hg. The compound obtained in crystalline form from acetonitrile has a m.p. of 106°-107°.

The following compound of formula IIa may be obtained in a manner analogous to that described in example 26 (example 27):

Example	R ₁	R ₂	R ₃	Configuration	Phys. chem. constants	For Ex.
27	H	H	CH ₃	4aRS, 5SR, 9bSR	M.P. 83°	23

EXAMPLE 28

(4aRS,5RS,9bRS)-1,3,4,4a,5,9b-hexahydro-2-methyl-5-phenyl-2H-indeno[1,2-c]pyridine (for examples 24 and 29)

5 a solution of 30 g. of 1,3,4,9b-tetrahydro-2-methyl-5-phenyl-2H-indeno[1,2-c]pyridine in 200 cc. of glacial acetic acid is shaken at 40° for 20 hours with a platinum oxide catalyst and

hydrogen at an initial pressure of 6 atmospheres. The catalyst is then filtered off, the solution is concentrated by evaporation in a vacuum, the residue is divided between a dilute caustic soda solution and methylene chloride, the methylene chloride solution is dried over magnesium sulfate and concentrated by evaporation. The resulting base is dissolved in isopropanol and a solution of hydrogen chloride in ether is added, whereupon (4aRS,5RS,9bRS)-1,3,4,4a,5,9b-hexahydro-2-methyl-5-phenyl-2H-indeno[1,2-c]pyridine hydrochloride crystallizes. After recrystallization from isopropanol the compound has a m.p. of 270°-272° (decomp.).

EXAMPLE 29

30 (4aRS,5SR,9bRS)-1,3,4,4a,5,9b-hexahydro-2-methyl-5-phenyl-2H-indeno[1,2-c]pyridine (for example 25)

10 g. of (4aRS,5RS,9bRS)-1,3,4,4a,5,9b-hexahydro-2-methyl-5-phenyl-2H-indeno[1,2-c]pyridine are boiled at reflux for 24 hours with a solution of 80 g. of potassium hydroxide in 200 cc. of butanol. The mixture is then poured on 1,000 cc. of water, is shaken out twice with ether, the ether solution is washed with a sodium chloride solution and after drying over magnesium sulfate is concentrated by evaporation. The resulting oil is dissolved in isopropanol and a solution of hydrogen chloride in ether is added, whereupon (4aRS,5SR,9bRS)-1,3,4,4a,5,9b-hexahydro-2-methyl-5-phenyl-2H-indeno[1,2-c]pyridine hydrochloride crystallizes. After recrystallization from isopropanol the compound has a m.p. of 287°-289° (decomp.).

50 51 yl-2H-indeno[1,2-c]pyridine hydrochloride crystallizes. After crystallization from isopropanol the compound has a m.p. of 287°-289° (decomp.).

EXAMPLE 30

55 (4aRS,5SR,9bSR)-7-chloro-5-p-chlorophenyl-1,3,4,4a,5,9b-hexahydro-2-methyl-2H-indeno[1,2-c]pyridine (for example 20)

60 61 100 g. of 4-(α -chloro- α -hydroxybenzyl)-3-p-chlorophenyl-1-methyl-piperidine are added portionwise within 15 minutes to 800 g. of polyphosphoric acid preheated to 110°. The reaction mixture is then stirred at the same temperature for 8 hours and is subsequently poured on a mixture of 3 kg. of ice and 1,500 cc. of methylene chloride while stirring. The mixture is subsequently made neutral with a concentrated caustic soda solution, the organic phase is separated and the aqueous phase is shaken out thrice with 1,000 cc. amounts of methylene chloride. The organic extracts are washed with water, dried over sodium sulfate and the solvent is removed by

70

distillation at reduced pressure. The oily residue is distilled in a high vacuum, whereby the primary fraction distils over as an oil at 195°–200°/0.01 mm. of Hg. The portion obtained in crystalline form from acetonitrile is a mixture of isomers having a m.p. of 95°–110°. A fumarate, having a m.p. of 224°–225°, is obtained from this mixture with fumaric acid in ethanol. This salt is divided between diethyl ether and a 2 N caustic soda solution, the ether phase is dried over magnesium sulfate and the solvent is removed, whereby (4aRS,5SR,9bSR)-7-chloro-5-p-chlorophenyl-1,3,4,4a,5,9b-hexahydro-2-methyl-2H-indeno[1,2-c]pyridine is obtained. After recrystallization from n-hexane the compound has a m.p. of 112°–114°.

EXAMPLE 31

(4aRS,5SR,9bRS)-7-chloro-5-p-chlorophenyl-1,3,4,4a,5,9b-hexahydro-2H-indeno[1,2-c]pyridine (for example 21)

The process is effected as described in example 30. After separating the fumarate, the mother liquor of the fumarate is completely concentrated by evaporation at reduced pressure and the residue is divided between diethyl ether and a 2 N caustic soda solution. After drying and concentrating the ether phase, the residue is recrystallized from n-hexane, whereby (4aRS,5SR,9bRS)-7-chloro-5-p-chlorophenyl-1,3,4,4a,5,9b-hexahydro-2-methyl-2H-indeno[1,2-c]pyridine, having a m.p. of 122°–125°, is obtained.

EXAMPLE 32

(4aRS,5SR,9bRS)-1,3,4,4a,5,9b-hexahydro-2,7-dimethyl-5-p-tolyl-2H-indeno[1,2-c]pyridine (for example 22)

12 g. of (4aRS,5RS,9bRS)-1,3,4,4a,5,9b-hexahydro-2,7-dimethyl-5-p-tolyl-2H-indeno[1,2-c]pyridine hydrochloride are added to a solution of 48 g. of potassium hydroxide in 120 cc. of n-butanol, and the mixture is heated in an oil bath of 150° for 18 hours. The cooled mixture is then poured on ice water and the aqueous phase is extracted thrice with 200 cc. amounts of diethyl ether. The extracts are dried over magnesium sulfate whereupon they are completely concentrated by evaporation at reduced pressure. The (4aRS,5SR,9bRS)-1,3,4,4a,5,9b-hexahydro-2,7-dimethyl-5-p-tolyl-2H-indeno[1,2-c]pyridine hydrochloride, obtained from alcohol/diethyl ether, has a m.p. of 305°–309° (decomp.).

EXAMPLE 33

4-(α -hydroxy-p-methylbenzyl)-1-methyl-3-p-tolyl-piperidine (for example 26)

a. 7.3 g. of magnesium are covered with a layer of absolute tetrahydrofuran, and a few crystals of iodine are added. A solution of 51.3 g. of p-bromotoluene in 100 cc. of absolute tetrahydrofuran is then added dropwise at such a rate that the reaction is kept going. The reaction mixture is then heated at reflux for 1½ hours, and a solution of 16.9 g. of 1,2,3,6-tetrahydro-1-methyl-isonicotinic acid ethyl ester in 50 cc. of absolute tetrahydrofuran is added to the resulting Grignard solution at reflux temperature. The reaction mixture is subsequently heated at reflux for one hour and 15 minutes, is then cooled to 10° and added with stirring to a mixture of 40 g. of ammonium chloride, 50 cc. of water, 50 g. of ice and 500 cc. of methylene chloride. After separating the organic phase, the aqueous phase is again shaken out thrice with 300 cc. of 65 methylene chloride, the combined extracts are dried over magnesium sulfate and the solvent is removed by distillation. The oily residue is distilled in a high vacuum, whereby 1-methyl-4-p-toluoyl-3-p-tolyl-piperidine distils over at 205°–210°/0.05 mm. of Hg. The compound obtained in crystalline form from diethyl ether/pentane has a m.p. of 107°–108°.

b. A solution of 28.5 g. of sodium borohydride in 100 cc. of water, stabilized with 6 cc. of a 5 N caustic soda solution, is added dropwise to a solution of 92.1 g. of 1-methyl-4-p-toluoyl-3-p-tolyl-piperidine in 600 cc. of ethanol within 30

minutes, at such a rate that the internal temperature does not exceed 40°. The reaction mixture is then stirred at 70° for 5½ hours, is subsequently evaporated to dryness at reduced pressure, and the residue is divided between 300 cc. of water and 300 cc. of chloroform. The organic phase is separated and the aqueous phase is again extracted twice with 100 cc. amounts of chloroform. The combined extracts are dried over magnesium sulfate, the solvent is removed by distillation at reduced pressure, and the residue, i.e. 4-(α -hydroxy-p-methylbenzyl)-1-methyl-3-p-tolyl-piperidine, is recrystallized from diethyl ether/pentane. m.p. 120°–123°.

10 The following compounds of formula V_a may be produced in a manner analogous to that described in example 33 (examples 34 and 35):

EXAMPLE 34 (for example 30 and 31)

- a. 4-p-chlorobenzoyl-3-p-chlorophenyl-1-methyl-piperidine, m.p. 118°–120°.
20 b. 4-(α -hydroxy-p-chlorobenzoyl-3-p-chlorophenyl-1-methyl-piperidine, m.p. 140°–142°.

EXAMPLE 35 (for example 27)

- 25 a. 4-benzoyl-1-methyl-3-phenyl-piperidine, b.p. 165°–180°/0.05 mm. of Hg.
b. 4-(α -hydroxybenzyl)-1-methyl-3-phenyl-piperidine, m.p. 153°–157°.

EXAMPLE 36

(4aRS,5RS,9bRS)-1,3,4,4a,5,9b-hexahydro-2,7-dimethyl-5-p-tolyl-2H-indeno[1,2-c]pyridine (for example 32)

35 a. A solution of 42 g. of 4-bromotoluene in 350 cc. of absolute diethyl ether is added dropwise within 10 minutes in an atmosphere of nitrogen to 3.5 g. of lithium wire cut in small pieces in 350 cc. of absolute diethyl ether. The mixture is subsequently heated at reflux for 1½ hours, is then cooled to –70° and a solution of 26.9 g. of 1,3,4,9b-tetrahydro-2,7-dimethyl-2H-indeno[1,2-c]pyridin-5(4aH)-one in 250 cc. of absolute diethyl ether is added within 30 minutes. The internal temperature of the solution is allowed to rise to 0°, stirring is continued at this temperature for 4 hours, and the reaction mixture is poured on 1,500 g. of ice and 1,500 g. of water, the aqueous phase is extracted with 6,000 cc. of chloroform, the extract is dried over magnesium sulfate and is almost completely concentrated by evaporation at reduced pressure.
40 b. 30.7 g. of 1,3,4,4a,5,9b-hexahydro-2,7-dimethyl-5-p-tolyl-2H-indeno[1,2-c]pyridinol crystallizes from chloroform diethyl ether. m.p. 210°–212°.

55 c. 30.7 g. of 1,3,4,4a,5,9b-hexahydro-2,7-dimethyl-5-p-tolyl-2H-indeno[1,2-c]pyridinol are heated at reflux for 2 hours in 200 cc. of 2.5 N hydrochloric acid in methanol. The solution is then completely concentrated by evaporation at reduced pressure. 1,3,4,9b-tetrahydro-2,7-dimethyl-5-p-tolyl-2H-indeno[1,2-c]pyridine hydrochloride, having a m.p. of 243°–245° (decomp.). is obtained from alcohol/diethyl ether.

60 The free base is obtained by dividing the hydrochloride between a 2 N caustic soda solution and chloroform, drying the chloroform extract over magnesium sulfate and concentrating at reduced pressure to a light yellow oil.

c. A solution of 26.4 g. of 1,3,4,9b-tetrahydro-2,7-dimethyl-5-p-tolyl-2H-indeno[1,2-c]pyridine in 200 cc. of glacial acetic acid is hydrogenated with 0.6 g. of platinum oxide at 40° and 4 atmospheres for 42 hours. After reduction is complete, the catalyst is filtered off and the filtrate is completely concentrated by evaporation at reduced pressure. The residue is taken up in 300 cc. of water, is made alkaline with dilute caustic soda solution and shaken out thrice with 200 cc. amounts of diethyl ether. The combined ether extracts are washed with water until neutral, are dried over magnesium

sulfate and the solvent is completely removed by distillation. The oily residue is then converted into the hydrochloride with the calculated amount of hydrochloric acid in ethanol. m.p. 252° (decomp.).

EXAMPLE 37

(4aRS,5SR,9bSR)-1,3,4,4a,5,9b-hexahydro-2-methyl-5-phenyl-2H-indeno[1,2-c]pyridine (for example 23)

a. 4-benzyl-1-methyl-3-phenyl-piperidinol-4.

15.6 g. of magnesium are covered with a layer of 120 cc. of absolute ether, a crystal of iodine and about 5 cc. of a solution of 81.4 g. of benzyl bromide in 400 cc. of absolute ether are added, and the mixture is heated until the reaction commences. The remainder of the above benzyl bromide solution is then added dropwise at such a rate that the solution boils continuously, and the solution is subsequently heated at reflux for a further 4 hours. A solution of 61.6 g. of 1-methyl-3-phenyl-piperidone-4 in 300 cc. of absolute ether is added dropwise at 10° to this benzyl magnesium bromide solution while stirring well, the reaction mixture is stirred at room temperature for a further 3 hours and is then allowed to stand at room temperature over night. The reaction mixture is then poured with stirring into a solution of 240 g. of ammonium chloride in 1,500 cc. of ice water, the entire material is filtered through diatomaceous earth, the organic phase is separated and the aqueous solution is again shaken out with ether. The combined ether solutions are washed with water, dried over potassium carbonate and concentrated by evaporation at reduced pressure. The residue is crystallized from n-hexane and yields 4-benzyl-1-methyl-3-phenyl-piperidinol-4, having a m.p. of 102°-104°.

b. (4aRS,5SR,9bSR)-1,3,4,4a,5,9b-hexahydro-2-methyl-5-phenyl-2-indeno[1,2-c]pyridine.

A mixture of 200 g. of polyphosphoric acid and 200 cc. of xylene is preheated to 130°, and a solution of 19 g. of 4-benzyl-1-methyl-3-phenyl-piperidinol-4 in 40 cc. of xylene is added within 30 minutes while stirring vigorously. The reaction mixture is stirred at 130° for 10 minutes, is cooled to 90° and poured on 600 cc. of ice water. The organic phase is separated, the aqueous portion is washed once with ether and is then saturated with potassium carbonate. The basic aqueous suspension is extracted with methylene chloride, the extract is washed with water and dried over potassium carbonate, whereupon the solvent is removed by evaporation at reduced pressure. The residue is distilled in a high vacuum, whereby (4aRS,5SR,9bSR)-1,3,4,4a,5,9b-hexahydro-2-methyl-5-phenyl-2H-indeno[1,2-c]pyridine distils over as an oil at 150°-155°/0.3 mm. of Hg. m.p. 82°-83° from hexane.

What is claimed is:

1. A (4aRS,5SR,9bSR)-, (4aRS,5SR,9bRS)- or (4aRS,5S,9bRS)-1,3,4,4a,5,9b-hexahydro-5-phenyl-2H-indeno[1,2-c]pyridine of the formula:

wherein R₁ is hydrogen, lower alkyl, fluorine, bromine or chlorine, and each of R₂, R₃ and R₄ are hydrogen, lower alkyl,

fluorine, bromine, chlorine, lower alkoxy, lower alkylthio or trifluoromethyl or a pharmaceutically acceptable acid addition salt thereof.

2. The compound of claim 1 which is (4aRS,5SR,9bSR)-1,3,4,4a,5,9b-hexahydro-7-methyl-2-phenacyl-5-p-tolyl-2H-indeno[1,2-c]pyridine.
3. The compound of claim 1 which is (4aRS,5SR,9bSR)-7-chloro-5-p-chlorophenyl-1,3,4,4a,5,9b-hexahydro-2-phenacyl-2H-indeno[1,2-c]pyridine.
4. The compound of claim 1 which is (4aRS,5SR,9bRS)-7-chloro-5-p-chlorophenyl-1,3,4,4a,5,9b-hexahydro-2-phenacyl-2H-indeno[1,2-c]pyridine.
5. The compound of claim 1 which is (4aRS,5SR,9bSR)-2-(4-bromophenacyl)-1,3,4,4a,5,9b-hexahydro-5-phenyl-2H-indeno[1,2-c]pyridine.
6. The compound of claim 1 which is (4aRS,5SR,9bSR)-2-(4-chlorophenacyl)-1,3,4,4a,5,9b-hexahydro-5-phenyl-2H-indeno[1,2-c]pyridine.
7. The compound of claim 1 which is (4aRS,5SR,9bSR)-1,3,4,4a,5,9b-2-(2,5-dichlorophenacyl)-1,3,4,4a,5,9b-hexahydro-5-phenyl-2H-indeno[1,2-c]pyridine.
8. The compound of claim 1 which is (4aRS,5SR,9bSR)-1,3,4,4a,5,9-hexahydro-2-(2-methyl-phenacyl)-5-phenyl-2H-indeno[1,2-c]pyridine.
9. The compound of claim 1 which is (4aRS,5SR,9bSR)-1,3,4,4a,5,9b-hexahydro-2-(3-methyl-phenacyl)-5-phenyl-2H-indeno[1,2-c]pyridine.
10. The compound of claim 1 which is (4aRS,5SR,9bSR)-1,3,4,4a,5,9b-2-(4-methyl-phenacyl)-5-phenyl-2H-indeno[1,2-c]pyridine.
11. The compound of claim 1 which is (4aRS,5SR,9bSR)-1,3,4,4a,5,9b-hexahydro-2-(3-methyl-phenacyl)-5-phenyl-1,3,4,4a,5,9b-hexahydro-7-methyl-2-phenacyl-2H-indeno[1,2-c]pyridine.
12. The compound of claim 1 which is (4aRS,5SR,9bSR)-1,3,4,4a,5,9b-hexahydro-2-(4-methyl-phenacyl)-5-phenyl-2H-indeno[1,2-c]pyridine.
13. The compound of claim 1 which is (4aRS,5SR,9bRS)-1,3,4,4a,5,9b-hexahydro-2-phenacyl-5-phenyl-2H-indeno[1,2-c]pyridine.
14. The compound of claim 1 which is (4aRS,5SR,9bRS)-1,3,4,4a,5,9b-hexahydro-2-phenacyl-5-phenyl-2H-indeno[1,2-c]pyridine.
15. The compound of claim 1 which is (4aRS,5SR,9bRS)-1,3,4,4a,5,9b-hexahydro-7-methyl-2-phenacyl-5-p-tolyl-2H-indeno[1,2-c]pyridine.
16. The compound of claim 1 which is (4aRS,5SR,9bRS)-1,3,4,4a,5,9b-hexahydro-2-p-methoxyphenacyl-2H-indeno[1,2-c]pyridine.
17. The compound of claim 1 which is (4aRS,5SR,9bRS)-7-chloro-5-p-chlorophenyl-1,3,4,4a,5,9b-hexahydro-2-methylphenacyl-2H-indeno[1,2-c]pyridine.
18. The compound of claim 1 which is (4aRS,5SR,9bRS)-7-chloro-5-p-chlorophenyl-2-(3,4-dimethoxyphenacyl)-1,3,4,4a,5,9b-hexahydro-2H-indeno[1,2-c]pyridine.
19. The compound of claim 1 which is (4aRS,5SR,9bSR)-1,3,4,4a,5,9b-hexahydro-2-phenacyl-5-phenacyl-2H-indeno[1,2-c]pyridine.
